ABSTRACT

The disclosure describes three analogous compounds, 1,3-bis(4-chlorophenyl)-2-propen-1-one guanylhydrazone hydrochloride, 1,3-bis(4-chlorophenyl)-2-buten-1-one guanylhydrazone hydrochloride, and 1,3,3-tris(4-chlorophenyl)-2-propen-1-one guanylhydrazone hydrochloride. The compounds are useful in the prevention and treatment of malaria.

1 Claim, No Drawings

**1,3-BIS(4-CHLOROPHENYL)-2-PROPEN-1-ONE
GUANYLHYDRAZONE HYDROCHLORIDE AND
ANALOGS THEREOF USEFUL AS
ANTIMALARIALS**

The invention herein described was made in the course of or under a contract or subcontract thereunder with the Department of the Army.

BACKGROUND OF THE INVENTION

Field of the Invention

This invention relates to 1,3-bis(4-chlorophenyl)-2-propen-1-one guanylhydrazone hydrochloride and analogs thereof, useful in the prevention and treatment of malaria. More specifically, it relates to three new antimalarial compounds, 1,3-bis(4-chlorophenyl)-2-propen-1-one guanylhydrazone hydrochloride, 1,3-bis(4-chlorophenyl)-2-buten-1-one guanylhydrazone hydrochloride, and 1,3,3-tris(4-chlorophenyl)-2-propen-1-one guanylhydrazone hydrochloride.

Description of the Prior Art

Malaria is one of the most widespread of all human diseases; it has been estimated that over 200 million people are afflicted and over a million die each year from malaria. Furthermore, contrary to popular belief, malaria is not confined to the tropical and subtropical regions; outbreaks have occurred almost as far north as the Arctic Circle and to a corresponding latitude south. It is a protozoan disease caused by several species of the genus *Plasmodium* which forms one of the families of the sub-order *Haempsorida*. *Plasmodium vivax* and *Plasmodium falciparum* are the most common species causing malaria in humans.

A number of antimalarial compounds have been prepared in the prior art, see for example the antimalarials section in Remington's *Pharmaceutical Sciences*, 13th edition (1965), pages 1302-1306. Recently, however, the prior art antimalarials have proved to be ineffective in specific cases in various parts of the world. The World Health Organization Technical Report No. 296 (1965), entitled "Resistance of Malaria Parasites to Drugs," reports the following cases of drug resistance: quinine sulfate failed completely against strains of *Plasmodium falciparum* from New Guinea; chloroquine, amodiaquine, mepacrine, pyrimethamine and proguanil gave poor results against *Plasmodium falciparum* and Thailand; chloroquine, mepacrine, pyrimethamine and proguanil were ineffective against *Plasmodium falciparum* from Cambodia; *Plasmodium falciparum* from Vietnam proved resistant to chloroquine; and chloroquine gave poor results against malaria in Malaya. Further instances of drug resistant malaria may be seen in L. Bruce-Chwatt, *Trans. Roy. Soc. Trop. Med. Hyg.* 59, 105-144 (1965), in L. Legters et al., *Military Med.* 130, 168-176 (1965), and in A. Bourke et al., *Trans. Roy. Soc. Trop. Med. Hyg.* 60, 225-230 (1966).

The only conclusion to be drawn from these reports is that there exists a great need for new antimalarial drugs.

SUMMARY OF THE INVENTION

This invention comprises the preparation of three new compounds and the discovery that these new compositions of matter are effective antimalarials. The

three new compounds, 1,3-bis(4-chlorophenyl)-2-propen-1-one guanylhydrazone hydrochloride, 1,3-bis(4-chlorophenyl)-2-buten-1-one guanylhydrazone hydrochloride, and 1,3,3-tris(4-chlorophenyl)-2-propen-1-one guanylhydrazone hydrochloride, have shown remarkable activity for the prevention and treatment of malaria in laboratory evaluation tests. The new compounds shown antimalarial activity that is completely unexpected.

Accordingly, it is an object of this invention to prepare new compositions of matter that are analogs of 1,3-bis(4-chlorophenyl)-2-propen-1-one guanylhydrazone hydrochloride.

Another object of this invention is to prepare new compositions of matter that are analogs of 1,3-bis(4-chlorophenyl)-2-propen-1-one guanylhydrazone hydrochloride and that possess antimalarial activity.

A further object of this invention is to provide new processes for the prevention and treatment of malaria in mammals, and particularly in humans, wherein the active ingredients are new analogs of 1,3-bis(4-chlorophenyl)-2-propen-1-one guanylhydrazone hydrochloride.

Finally, it is an object of this invention to prepare new compositions of matter that will be active against drug resistant malaria.

DESCRIPTION OF THE PREFERRED EMBODIMENTS

The new compositions of matter in this invention are prepared as follows:

EXAMPLE 1

35 Preparation of 1,3-bis(4-chlorophenyl)-2-propen-1-one guanylhydrazone hydrochloride

The first step in synthesizing the desired end product was to prepare the intermediate, 4,4'-dichlorobenzalacetophenone. This intermediate was 40 prepared according to the general procedure of E. P. Kohler and H. M. Chadwell in *Organic Synthesis*, 2nd edition (1948), Collective vol. 1, page 78, by reacting 4-chloroacetophenone and 4-chlorobenzaldehyde. The intermediate product was obtained in 83 percent yield and with a melting point of 153°-155° C. which compares favorably with the melting point of 155°-157° C. reported by H. O. House, *Journal American Chemical Society*, vol. 78 (1956), page 2298, for this intermediate compound.

50 The next step in the preparation of the desired end product was to slowly add adenoguanosine bicarbonate to a solution of 30 concentrated hydrochloric acid in 12 ml. of water. After the evolution of carbon dioxide had ceased, the intermediate 4,4'-dichlorobenzalacetophenone and ethyl alcohol were added. This suspension was refluxed with stirring. The precipitate was the desired end product, 1,3-bis(4-chlorophenyl)-2-propen-1-one guanylhydrazone hydrochloride.

55 It was recrystallized from ethyl alcohol and gave a melting point of 143°-153° C. The preparation resulted in a 14 percent yield. Thin-layer chromatography using silica gel and 10 percent methyl alcohol in chloroform revealed one component with an R_f of 0.25.

60 An elemental analysis gave the following results: Analysis calculated for C₁₈H₁₄Cl₂N₄HCl: C, 52.0; H, 4.09; N, 15.2. Found: C, 51.9; H, 4.20; N, 15.2.

EXAMPLE 2

Preparation of 1,3-bis(4-chlorophenyl)-2-buten-1-one guanylhydrazone hydrochloride

In the preparation of 1,3-bis(4-chlorophenyl)-2-buten-1-one guanylhydrazone hydrochloride, it was necessary to prepare the intermediate, 1,3-bis(4-chlorophenyl)-2-buten-1-one. This intermediate was prepared by the procedure of E. Ziegler and H. Schredt, in Monatsh. Chem., vol. 85 (1954), page 1191; Chemical Abstracts, vol. 50 (1956), page 321. 4-Chloroacetophenone (74 g., 0.51 mole) and 45 ml. of phosphorous oxychloride was held at 45° C. for 10 hours and then at 25° C. for 10 hours. The brown solution was poured over cracked ice and the oily product was extracted with ether. The ethereal solution was washed with water and dilute sodium carbonate solution and concentrated to yield 70 g. of oil. The crude product was dissolved in 150 ml. of ethyl alcohol and the solution was seeded. The crude yellow 1,3-bis(4-chlorophenyl)-2-buten-1-one melted at 75°-107° C. Two triturations with 500 ml. portions of methyl alcohol gave 16.5 g. (24 percent yield) of the intermediate, 1,3-bis(4-chlorophenyl)-2-buten-1-one, melting at 75°-80° C. This compares favorably with the report of Ziegler and Schredt, above, who gave a melting point of 80° C. for this compound.

Continuing in the preparation of the desired end product, aminoguanidine bicarbonate (3.0 g., 0.022 mole) was slowly added to a stirred solution of 32 ml. of water and 2.6 ml. of concentrated hydrochloric acid (0.031 mole). When the evolution of carbon dioxide ceased and the solution cleared, 6.0 g. (0.022 mole) of the intermediate, 1,3-bis(4-chlorophenyl)-2-buten-1-one, was added along with 50 ml. of ethyl alcohol. The mixture was refluxed overnight (solution attained) and then heated five hours longer. It was cooled and some of the ethyl alcohol was removed in vacuo. The precipitated solid which resulted was collected and titrated with diethyl ether to give 4.93 g. (59 percent yield) of the desired end product, 1,3-bis(4-chlorophenyl)-2-buten-1-one guanylhydrazone hydrochloride, melting at 235°-238° C. A portion of the product was recrystallized from 1:1 ethyl alcohol-water for an analytical sample melting at 245°-246° C.

An ultraviolet spectrum analysis gave the following results: $\lambda_{max. ethyl\ alcohol} = 207\ m\mu$ ($\epsilon = 31,300$), 274 $m\mu$ ($\epsilon = 31,300$).

An elemental analysis gave the following results: Analysis calculated for $C_{17}H_{16}Cl_2N_4HCl$: C, 53.3; H, 4.47; N, 14.6. Found: C, 53.1; H, 4.53; N, 14.8.

EXAMPLE 3

Preparation of 1,3,3-tris(4-chlorophenyl)-2-propen-1-one guanylhydrazone hydrochloride

The first step in the preparation of 1,3,3-tris(4-chlorophenyl)-2-propen-1-one guanylhydrazone hydrochloride was to prepare the first intermediate 1,1-bis(4-chlorophenyl)ethylene. This first intermediate was prepared by the addition of methyl magnesium bromide to 4,4'-dichlorobenzophenone and subsequent dehydration according to the procedure of O. Grummit et al. in Journal American Chemical Society, vol. 67 (1945), page 2265. The first intermediate 1,1-bis(4-chlorophenyl)ethylene was obtained in an 80 percent yield with a melting point of 83°-88° C. which

compared favorably with the results of Grummit et al., supra, who reported an 85 percent yield with a melting point of 84°-85° C.

The next step in the preparation of the desired end product was to prepare the second intermediate 1,3,3-tris(4-chlorophenyl)-2-propen-1-one. The procedure used to prepare this second intermediate is a modification of the general method of F. Bergman et al. in Journal Chemical Society, (1952), page 2522.

10 A solution of 17 g. (0.0683 mole) of the first intermediate 1,1-bis(4-chlorophenyl)ethylene and 13.15 g. (0.0751 mole) of 4-chlorobenzoyl chloride was heated to 240° C. At this temperature hydrogen chloride vapor evolved. The hydrogen chloride vapor was swept from the flask by a slow stream of nitrogen gas and monitored by bubbling through a sodium hydroxide solution containing phenolphthalein indicator. After about 18 hours, hydrogen chloride evolution ceased. The resulting black, solid reaction mixture was extracted with ethyl alcohol several times and the extracts were filtered. The solvent was removed from the combined filtrate and the residue was chromatographed on silica gel. Elution with carbon tetrachloride yielded starting materials and by-products. Elution with chloroform then gave 5.15 g. of moderately pure product, which was recrystallized several times from ethyl alcohol to yield 2.0 g. of pure product with a melting point of 135°-140° C. Thin-layer chromatography using silica gel and carbon tetrachloride showed one component with an R_f of 0.18.

15 An ultraviolet spectrum analysis gave the following results: $\lambda_{max. ethyl\ alcohol} = 233\ m\mu$ ($\epsilon = 22,000$), 271 $m\mu$ ($\epsilon = 18,600$), 318 $m\mu$ ($\epsilon = 14,000$).

20 An elemental analysis gave these results: Analysis calculated for $C_{21}H_{13}Cl_3O$: C, 65.1; H, 3.38. Found: C, 65.6; H, 3.45.

25 The final step in the preparation of the desired end product was to slowly add aminoguanidine bicarbonate to a solution of concentrated hydrochloric acid in water. After the evolution of CO_2 had ceased, the second intermediate 1,3,3-tris(4-chlorophenyl)-2-propen-1-one and 46 ml. of ethyl alcohol were added. This suspension was refluxed with stirring for 16 hours.

30 The initial preparation of this compound gave analytical samples of both a dehydrated (melting point 165°-170° C.) and an unhydrated (melting point 210°-220° C.) product. A second preparation gave 1.5 g. (43 percent yield) of hydrated product.

35 An infrared spectrum analysis gave the following results: $\lambda_{max. NHOH} = 2.95 - 3.25\ \mu$ (NH functional group) and $5.96\ \mu$ (C=N functional group).

40 An elemental analysis gave the following results: Analysis calculated for $C_{22}H_{17}Cl_3N_4HCl \cdot H_2O$: C, 53.0; H, 4.01; N, 11.2. Found: C, 52.8; H, 4.21; N, 11.4.

ANTIMALARIAL UTILITY

45 The three new compositions of matter prepared in the above examples show unexpected and unobvious antimalarial activity. This fact can be seen in the following table which gives the results of antimalarial evaluations using the Walter Reed Army Institute of Research primary mouse screen test on a series of analogs of 1,3-bis(4-chlorophenyl)-2-propen-1-one guanylhydrazone hydrochloride.

ANTIMALARIAL EVALUATION OF COMPOUNDS

Example	Structure	Antimalarial bioassay results ¹									
		20 mg./kg. ²	40 mg./kg. ²	80 mg./kg. ²	160 mg./kg. ²	320 mg./kg. ²	640 mg./kg. ²				
1		0.4	5.9	9.6	17.0	3/6 C	5/6 C	5/6 C			
2		{	—	4.1	—	21.9	3/6 C	—	5/6 C		
			1.0	4.5	14.9	3/6 C	19.4	3/6 C	23.9	3/6 C	5/6 C
3		—	0.1	0.4	0.9	5.8	17.1	3/6 C			

¹ Increase in survival time (in number of days) of treated mice beyond that of untreated controls after single subcutaneous dosages (three days post-infection) of 20, 40, 80, 160, 320 and 640 mg. of drug per kg. of body weight. Average survival time of untreated mice: 6.5 plus or minus 0.5 days. Infecting organism: *Plasmodium berghei*. Quinine gives values of approximately 1.0 at 40 mg./kg., 3.0 at 160 mg./kg. and 7.0 at 640 mg./kg. in this test. A fraction followed by the letter "G" indicates cured mice over total mice in the treated group. Drug toxicity is assumed to be the cause of death when treated mice die before untreated controls. A dash indicates tests were not run at this dosage. Five mice were used in each test run at a specific dosage level. In some instances, repeat test runs were performed.

² Dosage in milligrams of drug per kilogram of mouse weight.

DISCUSSION OF ANTIMALARIAL EVALUATION

The antimalarial evaluation reported in the above table reveals remarkable antimalarial activity in 1,3-bis(4-chlorophenyl)-2-propen-1-one guanylhydrazone hydrochloride (Example 1), 1,3-bis(4-chlorophenyl)-2-buten-1-one guanylhydrazone hydrochloride (Example 2) and in 1,3,3-tris(4-chlorophenyl)-2-propen-1-one guanylhydrazone hydrochloride (Example 3).

Testing antimalarial compounds in humans is obviously too dangerous for the first step in the development of antimalarials. Thus, animal tests have conventionally been used to test antimalarial compounds and animal tests have led to the development of many of the antimalarial compounds now available such as quinacrine, chloroquine, pamaquine, and proquanil.

The Walter Reed Army Institute of Research uses the primary mouse screen with *Plasmodium berghei* for

several reasons. One reason is that the *Plasmodium* species which cause malaria in humans (i.e., *Plasmodium falciparum* and *Plasmodium vivax*) cannot live in animals. Another reason is that *Plasmodium berghei* is regarded as a good model for human malaria. Finally, mice are easy to work with and the *Plasmodium berghei* infections show the same range of susceptibility to a variety of known antimalarial drugs as other malaria parasites used for evaluating antimalarial compounds. See for example Bull. Soc. Pathol. Exotique 42, 449 (1949); Ann. Trop. Med. Parasitol. 44, 291 (1950); Brit. J. Pharmacol. 8, 162 (1953); Z. Tropenmed. U. Parasitol. 2, 471 (1951).

I claim:

1. 1,3-Bis(4-chlorophenyl)-2-buten-1-one guanylhydrazone hydrochloride.
